UNITED STATES PATENT OFFICE.

DANIEL W. ZEBER, OF AVALON, PENNSYLVANIA.

DESIGN FOR A BOTTLE.

SPECIFICATION forming part of Design No. 30,759, dated May 16, 1899.

Application filed February 23, 1899. Serial No. 706,587. Term of patent 14 years.

To all whom it may concern:

Be it known that I, DANIEL W. ZEBER, a citizen of the United States, residing at Avalon, in the county of Allegheny and State of Pennsylvania, have invented a new and original Design for Bottles, of which the following is a specification, reference being had therein to the accompanying drawings, forming part thereof, in which—

10 Figure 1 illustrates a side view of a bottle embodying my design. Fig. 2 is a cross-section through the neck thereof, and Fig. 3 is a cross-section through the body thereof.

15 The leading features of my design consist in a bottle of the particular shape or configuration illustrated, having formed on and as part of the neck thereof the representation of a strip or ribbon tied in a slip or bow knot, substantially as herein shown and described.

20 As shown in the different figures of the

drawings, 1 represents a bottle having the body 2 and neck 3. 4 represents the strip or ribbon formed around and as part of the neck 3 of the bottle 1, and 5 represents the slip or bow knot formed around and as part of the 25 neck 3 of the bottle 1 by the ends 6 of the strip or ribbons 4 thereof.

What I claim as my invention, and desire to secure by Letters Patent, is—

The design for a bottle, substantially as 30 herein shown and described.

In testimony whereof I have hereunto set my hand, at Pittsburg, in the county of Allegheny and State of Pennsylvania, this 18th day of February, A. D. 1899.

DANIEL W. ZEBER.
